HENRY F. SCHMIDT, OF LANSDOWNE, PENNSYLVANIA, ASSIGNOR TO WESTINGHOUSE ELECTRIC & MANUFACTURING COMPANY, A CORPORATION OF PENNSYLVANIA

PUMP

Application filed January 21, 1928. Serial No. 248,443.

My invention relates to fluid translating apparatus and more particularly to propeller type blowers or pumps, and it has for an object, to improve the efficiency of apparatus 5 of this character.

Another object is to provide means for improving the efficiency of diffusers having relatively large angles of divergence.

Apparatus exemplifying the features of 10 my invention is shown in the accompanying drawings, forming a part of this specification, wherein:

Fig. 1 is a section through a convergent-divergent channel;

15 Fig. 2 is a diagrammatic view;

Fig. 3 is a section through a convergent-divergent channel; and

20 Fig. 4 is a section through the casing of a propeller type blower, and showing the rotor elements in elevation.

In the flow of fluid through a convergent-divergent channel it sometimes occurs, especially where the divergent portion has relatively large angles of divergence, that the 25 fluid does not follow the walls of the diffuser, but issues from the throat in the form of a jet, which passes through the central portion of the diffuser, leaving dead spaces and vortices adjacent the walls thereof, as is clearly 30 shown in Fig. 1, in which the direction of flow through the convergent-divergent channel 10 is indicated by the arrows, the path of particles of fluid being indicated by the fine lines within the channel. This condition 35 should, of course, be avoided, as the fluid passes directly through the diffuser without undergoing velocity-pressure conversion.

The conditions shown in Fig. 1 are caused 40 by conditions somewhat analogous to those shown in Fig. 2, in which a ball 11, if it experiences no friction, would pass, from a state of rest at 12, down the inclined plane 13 to the base thereof, and up the inclined plane 14 to the position 15, which is at the 45 same elevation as the position 12. However,

due to the friction of the ball with the surface of the inclined planes, the ball on reaching the base of the plane 13 does not have sufficient kinetic energy to carry it to the top of plane 14, but comes to rest at some position, such as that indicated at 16, and then runs back down the plane 14.

50 Due to friction, particles of fluid adjacent the walls of the diffuser behave similarly to the ball 11 shown in Fig. 2. Considering Fig. 3, each element of fluid flowing from the region, indicated by the reference character 55 17, to the throat of the convergent-divergent channel 10 would acquire velocity from the fall of pressure between these two points. 60 The kinetic energy of a particle of fluid at the throat would, therefore, in the case of a perfect fluid, be sufficient to enable it to pass through the diffuser against the adverse pressure head, but due to the friction between the 65 walls of the diffuser and the particles of fluid, there is a retarded flow along these walls which is accumulative, and the more rapid flow of elements of fluid nearer the center of the stream have a tendency to produce vortices such as the vortices 19 and 21, indicated 70 in Fig. 1. These, in turn, may produce auxiliary eddies 22 and 23, which may have a whirling motion in the opposite direction to that of the vortices 19 and 21. It will be 75 understood, of course, that the vortices and other eddy currents are unstable and some break away and are carried down the stream leaving dead spaces on either side of the jet.

80 In order to overcome these objectionable features, I have provided means for causing the elements of fluid to follow the walls of the diffusing cone. In Fig. 3, I show a suitable number of passages 26 and 27 which afford communication between suitable openings such as holes, or slots 28 about the diffusing cone and similar openings 29 about the convergent portion of the convergent-divergent channel. The relatively low pressure 85 90

in that portion of this channel which converges in the direction of fluid flow, causes fluid to be drawn from the vicinity of the walls of the diffuser through the passages 26 and 27 and into the convergent portion. In this way, the fluid is assisted to follow the walls, and eddy currents, vortices and the like are avoided.

In Fig. 4 I show a propeller 31 within a convergent-divergent casing 10', the latter being provided with passages 26, 27 arranged as described with reference to Fig. 3. In this case, however, each end of the tubular passages, 26, 27, is connected to a suitable box 32 which fits against the casing 10' and encloses one of the slotted holes 28 or 29. A suitable prime mover, such as a turbine 33, is connected to operate the propeller 31, and disposed in the divergent portion of the channel are suitable guide vanes 34.

Any suitable number of passages, such as 26, 27 may be provided, and the holes 28 in the diffuser are, preferably, at different distances from the throat of the channel, as shown, in order to insure the particles of fluid following the walls for the entire length of the diffusing cone. The holes 28 serving each set of passages 26, 27, may be arranged in circumferential rows, and, if desired the holes in one row may be staggered with respect to those in the next, in order to further reduce any tendency for retarded flow.

While a plurality of the openings 28 in the diffuser may be connected by a common passage to the convergent portion of the casing, I prefer to have independent passages for each opening in the diffusing cone in order to avoid the possibility of merely short circuiting fluid from one opening in the diffusing cone to another.

In this way it is possible to obtain the desired velocity-pressure conversion with a relatively short diffusing cone. This becomes important in propeller type pumps, blowers, and the like, for the diffusing cone often encompasses a portion of the prime mover, such as the turbine 33, so that it is difficult to gain access to various parts of the prime mover, as for example to the gland. By using a shorter diffusing cone, this objection is overcome.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

60 What I claim is:

1. The combination with a convergent-divergent channel, of means providing one or more exterior passages between the divergent and the convergent portions of the channel.
- 65 2. The combination with a convergent-di-

vergent casing of a propeller type blower, of means providing one or more passages outside of the casing and communicating between the divergent-convergent portions thereof.

3. The combination with the convergent-divergent casing of a propeller type pump, of means providing a plurality of circumferentially spaced openings about the divergent portion of the casing, and means for conducting fluid from said openings into the convergent portion of said casing.

4. The combination with the convergent-divergent casing of a propeller type pump, of means providing a plurality of axially spaced openings about the divergent portion of the casing, and means for conducting fluid from said openings into the convergent portion of said casing.

5. The combination with the convergent-divergent casing of a propeller type pump, of means providing a plurality of circumferentially and axially spaced openings about the divergent portion of the casing, and means for conducting fluid from said openings into the convergent portion of said casing.

In testimony whereof, I have hereunto subscribed my name this seventeenth day of January, 1928.

HENRY F. SCHMIDT.
